(57) **CLAIM**

The ornamental design for an aromatherapy lamp base, as shown and described.

DESCRIPTION

FIG. 1 is a top, front and right side perspective view of an aromatherapy lamp base, showing my new design; FIG. 2 is a bottom, front and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The lamp cap and lamp elbow outlined by broken lines assists in illustrating how the aromatherapy lamp base may appear when in a position of use, but forms no part of the claimed design.
